(57) **CLAIM**

The ornamental design for a hand held tool, as shown and described.

DESCRIPTION

FIG. 1 is a perspective view of a first embodiment of a hand held tool showing my new design;

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is a perspective view of a second embodiment of a hand held tool showing my new design;

FIG. 8 is a front view thereof;

FIG. 9 is a rear view thereof;

FIG. 10 is a right-side view thereof;

FIG. 11 is a left-side view thereof; and,

FIG. 12 is a top view thereof.

The bottom view has been omitted and forms no part of the claimed design. The broken lines shown in FIGS. 1–12 represent environmental subject matter and form no part of the claimed design.
